(57) **CLAIM**

The ornamental design for a dental toothpaste strip, as shown and described.

DESCRIPTION

FIG. 1 is a perspective view of a dental toothpaste strip showing my new design.

FIG. 2 is a side elevational view of FIG. 1, the opposite side is a mirror image thereof;

FIG. 3 is a top plan view of FIG. 1;

FIG. 4 is an end elevational view of FIG. 1, the opposite end is a mirror image thereof; and,

FIG. 5 is a bottom plan view of FIG. 1.

The ends of the dental toothpaste strip are shown broken away and indicate an indeterminate length.
